UNITED STATES PATENT OFFICE.

HERBERT DUNDERDALE, OF CLEVELAND, OHIO.

DOOR-LOCK.

1,250,816.

Specification of Letters Patent. Patented Dec. 18, 1917.

Application filed August 26, 1915. Serial No. 47,413.

To all whom it may concern:

Be it known that I, HERBERT DUNDERDALE, a citizen of the United States, residing at Cleveland, in the county of Cuyahoga and State of Ohio, have invented certain new and useful Improvements in Door-Locks, of which the following is a full, clear, and exact description, reference being had to the drawings herein.

10 My invention pertains to door locking devices, and has reference more particularly to a lock device designed for use in connection with the rear edge of a sliding door.

The invention has for one of its principal 15 objects the provision of a two-part lock device of this character co-acting to draw the rear edge of the door sidewise against the doorway frame as the door is moved to closed position and thereby provide a tight 20 closure at the rear of the door, and in which position the door is locked by the device against lateral or vertical movement.

Another object is to produce a simple and 25 efficient lock device of this character wherein binding of the parts is eliminated, and which is cheaply constructed, easily applied, and facile and positive in its operation.

A further object is the provision of a 30 lock device constructed to provide for, and to correct, in the closing movement of the door any sagging of the door which may be present.

These, together with such other objects as may hereinafter appear, or are incident 35 to my invention, I attain by means of a construction illustrated in preferred form, wherein:—

Figure 1 represents a horizontal sectional view illustrating the application of my improved door lock device to a door;

Fig. 2 is a front elevation of the same;

Fig. 3 is an end view of the device along the line III—III of Fig. 2;

Fig. 4 is a view in perspective of the two 45 co-acting lock members which together comprise the lock device; and

Fig. 5 represents a slightly modified form of my invention.

Referring to the drawings, the numeral 7 50 indicates the doorpost located at the side of the doorway, 8 the siding and 9 a fragmentary portion of a sliding door; the doorpost having a portion 7^a thereof projecting outwardly beyond the siding 8 to provide a 55 clearance between it and the door for the

reception of my lock device, which latter operates to draw the rear edge 10 of the door tightly up against the projecting portion of the door post and locks the door against vertical and lateral movement when the door 60 is closed.

The lock device, as shown, consists of a locking slide member A, and a receptive socket member B of elongated shape preferably secured to the siding closely adjacent 65 to the projecting portion 7^a of the doorpost; the slide member being correspondingly mounted on the inner face of the rear edge 10 of the door, and which comprises a base or attaching portion 11, having integrally 70 formed therewith a neck 12 and a head 13 which extend into the clearance between the door and siding.

The socket member B of the device is disposed in the clearance and comprises the 75 central web portion 19, attaching base flanges 15 formed with bolt holes 15^a for the reception of the attaching bolts 16 which pass into the siding, and connecting side walls 14^a. The web portion 19 is longitudinally inclined inwardly from its wide open outer end to its inner end to provide an inner inclined face 21 and formed with a slot leading from said wide open end to a narrow terminal seat 18^a adjacent the inner 80 end of the member, the slot being inclined to said seat to form a slideway 18 for the neck 12 and having at each side thereof guiding flanges 14 extending outwardly from the seat to the wide open end and 85 whose inner inclined faces are designed to be slidably engaged by the head 13 to draw the rear end of the door inwardly against the port 7^a as the neck travels in the slot or up the slideway 18 to the seat 18^a to properly center the door.

On opening the door, the locking slide member disengages easily from the socket, the construction of the members being such that gripping or binding of the parts is positively eliminated. In this connection it is considered important that the head 13 be of a length considerably less than the distance between the side walls 14^a in order to prevent any contact whatever of the same, particularly at either of the low or high points of the slideway. In this way the neck 12 co-operating with the slideway centers the door and locks it against vertical displacement, and the head in turn co-operating with 110

the inclined face of the socket draws the door tightly against the doorpost or frame and holds it against lateral movement.

In practice it is considered preferable, 5 that when the door is closed, the rear edge 10 thereof should project over the restricted end 19 of the socket sufficiently enough to cover the heads of the rear set of bolts 16 in order to prevent unauthorized removal of 15 the socket member.

From the foregoing, the essential features, 10 elements, and the operation of my locking device, together with its simplicity and other advantages thereof, will be clearly apparent 15 to those skilled in the art.

Having thus described my invention and 10 illustrated its use, what I claim as new and desire to secure by Letters Patent, is the following:—

20 1. In a door closure and lock device, the combination of a socket member comprising a base and a socket portion having its outer end provided with a wide opening disposed substantially at right-angles with reference 25 to said base, said socket portion formed longitudinally with an inclined slot leading from said wide open end to provide a relatively narrower terminal seat adjacent the inner end of the socket portion and having 30 guide flanges extending outwardly from the seat to said open end at each side of the slot, and a relatively smaller sliding bolt member constructed and arranged to enter and pass through said open end for inward 35 sliding travel in the slot to engage in said seat, said guide flanges inclined in an inward direction toward said base and coöperating with the slot to guide the bolt member in its inward travel to said seat.

40 2. In a door closure and lock device, the combination of a socket member comprising an attaching base and an inclined socket portion having its outer end provided with a wide opening disposed substantially at right- 45 angles with reference to said base, said socket portion having its web partially formed longitudinally with an angular slot leading from said wide open end to provide at its apex a relatively narrower terminal 50 seat in the inner end of the member and an inclined slideway extending intermediately of said wide outer opening and the narrow seat, that portion of the web bounding the slot constituting a flanged guide means having 55 an inner inclined face, and a sliding bolt member adapted to enter and pass through said wide open end to said seat and comprising an attaching base having a head adapted to slidably engage said inner inclined face 60 and an intermediate neck portion adapted to slidably engage said slideway in its travel to said seat.

3. In a door closure and lock device, the combination of an elongated socket member 65 having an open outer end and comprising

a base and a central body portion having a part of its web cut away longitudinally to provide a seat adjacent its inner end and spaced upper and lower guide flanges extending outwardly from the seat to said open outer end, the lower guide flange having an upwardly inclined face constituting a slideway to said seat and both of said flanges having inwardly inclined inner guide faces disposed substantially at right angles to said 75 slideway, and a relatively smaller sliding bolt member constructed and arranged to enter and pass through said open outer end to said seat and comprising angularly disposed locking portions adapted to slidably 80 engage said slideway and said inner guide faces, respectively, substantially as described and for the purpose set forth.

4. In a door closure and lock device, the combination with a sliding car door and car 85 siding having a doorway opening therein, of a longitudinally disposed socket member secured to the car siding adjacent the rear end of said opening and having an open outer end disposed substantially at right- 90 angles to said siding, said member comprising an attaching base and a central body portion having a part of its web recessed longitudinally and angularly to provide a restricted seat adjacent its inner end and 95 spaced upper and lower guide flanges extending in an outward direction from the seat to said outer open end, the lower guide flange having an upwardly inclined face constituting a slideway to said seat and said 100 guide flanges having inwardly inclined inner guide faces disposed substantially at right angles to said slideway and at each side thereof, and a sliding bolt member secured to the rear portion of the door and 105 adapted to enter and pass through said outer open end to engage the seat, said member comprising horizontally and vertically disposed locking portions constructed and arranged for slidably engaging said slideway 110 and said inner guide faces, respectively, the horizontal locking portion adapted to maintain the door against movement in a vertical plane and the vertical locking portion adapted to maintain the door against outward 115 movement in a horizontal plane when said member is seated.

5. In combination, a door frame and its opening; a sliding door for said opening, 120 said door frame provided with a door post projecting outwardly beyond the outer face of the frame to provide a clearance between the door and said frame; and a lock device for said door comprising a longitudinally disposed socket member having an open outer end and comprising side walls and an intermediate inclined body portion having a part of its web formed with an angular recess whose wide end merges with said open outer end and whose narrow end is termi- 125 130

nally located adjacent the other or inner end of the member, that portion of the web bounding the recess constituting a flanged guide means having an inner inclined face 5 and a slideway both disposed intermediately of said side walls and extending from said open outer end to said narrow terminal end, and a sliding bolt member adapted to pass through said wide open end to the narrow terminal end of the recess comprising angularly disposed locking portions constructed and arranged for slidable engagement with said inner inclined face and slideway, said

members carried by said door and frame and coöoperating in said clearance to lock the 15 door against the door-post and respectively maintain the door against lateral and vertical displacement.

In testimony whereof I have hereunto signed my name and affixed my signature in 20 the presence of the subscribing witnesses.

HERBERT DUNDERDALE.
